ABSTRACT: A pulse current modulator utilizes a pair of complementary transistors having interconnected collectors connected via a diode to an output load. The transistors are energized by an operating voltage connected across their emitters. The base of one of the transistors receives the amplitude modulated signal which is to be pulse control modulated while the base of the other transistor receives constant amplitude pulses to provide the pulse times of modulation.

MODULATOR DEVICE

MODULATOR DEVICE

The present invention concerns an arrangement for pulse current modulation, especially for pulse current modulation, especially for a telephone system of the time division multiplex type (TDM-system) in which a current pulse proportional to the instantaneous value of an analogue signal, usually a speech signal, is to be generated at times fixed by a control signal.

In one type of modulators, the modulated signal is obtained in the form voltage pulses, the amplitudes of which correspond to the analogue signal. This however, implies some disadvantages since difficulties arise during voltage transmission due to the fact that the reference level on the transmitter side and the reference level on the receiver side cannot be kept identical but are affected by dynamic processes in other parts of the system.

The present invention makes use of the properties of a current modulator having a variable output impedance, which makes it possible for the modulator to adapt its impedance to the instantaneous value of the reference potential and to supply a current, the amplitude of which is proportional to the analogue signal. Such modulators are known, for example by the Swedish Pat. No. 199,431. Compared with said patent the modulator according to the invention presents certain advantages as will appear from the description.

An arrangement for pulse current modulation according to the invention is characterized thereby that the collectors of two transistors of different conductivity type are interconnected and in turn connected to a diode. Supplied to the base of one of the transistors is an analogue signal and supplied to the base of the other transistor is a pulsating control signal whereby the collector current of the first-mentioned transistor varies proportionally to said analogue signal while the other transistor is alternatively blocked or conducting in dependence on said control signal. Thus in the interval between the pulses of the control signal, the transistor is conducting, its collector current being equal to the collector current of the first-mentioned transistor, and the diode is biased, so that it is blocked. When however, the other transistor is blocked, the diode is conducting, so that a current pulse proportional to the instantaneous value of the analogue signal will pass through the diode at times fixed by the control signal.

Furthermore, if the first-mentioned transistor is provided with a high emitter impedance it practically works like a pure current amplifier.

In order to obtain a smooth and distortionless modulation, the base of the first-mentioned transistor can be connected through a resistance to a bias source and the analogue signal supplied to the base through a capacitor, so that the modulator becomes independent of the possible direct voltage variations of the input signal.

The invention will be described with reference to the accompanying drawing which shows a circuit diagram of an arrangement according to the invention.

The arrangement shown in the FIGURE comprises two transistors T_1 and T_2 of different conductivity type, their collectors K_1 , K_2 being interconnected and connected to a diode D. The transistors T_1 and T_2 are shown as a PNP- and NPN-types respectively. The base of the transistor T_1 is connected to a bias source U_b , via a resistance R_b , and an analogue signal V_{in} is supplied to the base via a capacitor C_a . The emitter of the transistor T_1 is connected to a stable reference potential O via an impedance Z_E . To the same reference potential O there is also connected the base of the transistor T_1 via a capacitor C_{b1} . The capacitance of capacitor C_B is preferably much higher than the collector-base capacitance of the transistor (On the drawing the collector-base capacitance is indicated by dashed lines).

The base of the transistor T_2 is connected to a rather high, positive potential, via resistance R_2 , so that the transistor T_2 is

conducting, and, quiescently, a current I_c passes from the collector to the emitter of transistor T_2 which is connected to a negative potential $-P_1$. The potential the collectors K_1 and K_2 will thus be very close to the potential $-P_1$. The diode D is connected to a negative potential $-P_2$ through a resistance R_M , and said negative potential is chosen so, that the diode D is back biased when the transistor T_2 is conducting i.e. the potential $-P_1$ is lower than the potential $-P_2$.

At recurrent times negative voltage pulses A of such amplitude to block transistor T_2 are supplied to the base of the transistor T_2 . The collector voltage of the transistor T_1 will then shift to the reference potential O. Now the diode D will be conducting and a current I_A can pass through the resistance R_M . If the voltage $-P_2$ is unstable, the amplitude of the voltage pulse V_A will have different values for a given current I_A depending on the variation of the voltage $-P_2$. However, by arranging the transistor T_1 in such a way that its output impedance changes according to the amplitude of the voltage pulses V_A , the current I_c and thus the current I_A will be kept relatively constant and relatively independent of the voltage $-P_2$, i.e. the current will solely be a function of the input voltage V_{in} . The voltage U_m across the resistance R_m will thus be proportional to the analogue signal V_{in} , said voltage being relatively independent of variations in the voltage $-P_2$.

25 In order to have the current I_c relatively constant and relatively independent of the voltage of the collector K_1 , the circuit including the transistor T_1 must be dimensioned carefully. The output impedance of the transistor T_1 will be very high due to the emitter impedance Z_E . When the collector of the 30 transistor T_1 is exposed to the voltage pulses V_A , the inner feedback of the transistor, mainly caused by the collector-base capacitance, tends to decrease the current I_c . This, however, can be compensated by means of a capacitor C_B connected to the base. The capacitance of said capacitor C_B must be considerably higher than the collector-base capacitance indicated by dashed lines on the drawing, whereby the base potential will be only insignificantly affected. By an appropriate choice of the values of the impedance Z_E and the capacitor C_B —obvious to a man skilled in the art—the output impedance of the 35 transistor T_1 can be made to vary, so that the current I_A and thus the voltage U_m become relatively independent of the voltage $-P_2$ and linear functions of the analogue signal V_{in} .

We claim:

1. A pulse current modulator for generating current pulses 45 having amplitudes proportional to the instantaneous amplitudes of an analogue signal comprising first and second transistors, said transistors being of complementary types, each of said transistors having base, emitter and collector terminals, said collector terminals being interconnected, means 50 for applying an operating potential across the emitter terminals of said transistors, a second potential source, a diode means, means for connecting said diode means between the interconnected collector terminals and said second potential source, the potential of said second potential source being 55 chosen with respect to the potential of said first potential source to render said diode means nonconducting when both of said transistors are conducting and to render said diode means conducting when said first transistor is conducting and said second transistor nonconducting, means for applying the 60 analogue signal to the base terminal of said first transistor, and means for applying periodic signal pulses to the base terminal of said second transistor for switching said second transistor between conducting and nonconducting states whereby a current pulse having an amplitude related to the instantaneous 65 amplitude of the analogue signal is transmitted via said diode means whenever said second transistor is nonconducting.

2. The modulator of claim 1 further comprising a capacitor 70 connecting the base terminal of said first transistor to said source of operating potential for minimizing any signal feedback between the collector and base terminals of said first transistor.
